UNITED STATES PATENT OFFICE.

WILLIAM J. SNADECKI, OF BRIDGEPORT, CONNECTICUT, ASSIGNOR TO RICHARD CRANE, OF WASHINGTON, DISTRICT OF COLUMBIA.

INTERNAL-COMBUSTION MOTOR.

Application filed June 14, 1917. Serial No. 174,788.

To all whom it may concern:

Be it known that I, WILLIAM J. SNADECKI, a citizen of the United States, residing at Bridgeport, in the county of Fairfield and State of Connecticut, have invented certain new and useful Improvements in Internal-Combustion Motors, of which the following is a specification, reference being had therein to the accompanying drawing.

10 My invention relates to improvements in internal combustion engines and more particularly has reference to means in combination therewith for cooling the lubricating oil thereof and also preferably simultaneously heating the air fed to the engine cylinders.

It is well known that in most types of internal combustion engines that the lubricating oil upon coming in contact with the cylinder walls becomes highly heated thereby causing various forms of trouble well known to those skilled in the art. One of the principal objects of this invention is to provide a suitable and convenient method 25 of reducing the temperature of this lubricating oil while at the same time utilizing in a practical manner the heat drawn therefrom.

Referring to the accompanying drawings 30 I have illustrated in Fig. 1 with parts broken away the lower part of an engine casing and an attachment illustrating an embodiment of my invention, and Fig. 2 is a view looking from right to left thereat.

35 3 indicates the engine casing beneath the cylinders and in which it is common practice to carry a supply of lubricating oil.

4 indicates a suitable tank or chamber which may be suspended therefrom by brackets.

40 such as 5 or which may be secured in any suitable manner, and 6 indicates suitable tubes or passages through which the oil from the casing 3 may feed into the chamber 4.

7 indicates a series of tubes engaged in 45 the heads 8—9 forming the ends of the chamber 4, through which air is allowed to pass completely, thus providing a large tubular surface which may be cooled by atmospheric air and which may be kept in 50 contact with the lubricating oil. From the foregoing it will be seen that any desired quantity of lubricating oil may be thus provided for and may be thus kept in contact with a large surface, thereby insuring 55 a decidedly reduced temperature of the oil. 10 indicates a suitable tube provided with a head such as 11 through which the air may be drawn through the tubes 7 for supplying the same to the carburetor, thus providing a suitable draft and means for carrying off the heated air for advantageous use. Of course it will be understood that any suitable connections may be made with the chamber 4 for providing any well 60 known or desirable circulation of the oil therein, and of course it will be understood that various modifications may be made in the construction and arrangement of parts without departing from the spirit of the 65 invention as claimed.

I claim:—

In combination with an internal combustion engine, tubes through which the air for combustion is passed, means in combination therewith for circulating the lubricating medium of said engine around said tubes, said tubes in a chamber beneath the crank case and a space between said chamber and said crank case for the circulation 75 of air.

In testimony whereof I hereunto affix my signature in the presence of two witnesses.

WILLIAM J. SNADECKI.

Witnesses:

ANNA F. DUFFY,
ETHEL GARDNER.
